UNITED STATES PATENT OFFICE.

GEORGE L. PREBLE, OF LYNN, MASSACHUSETTS.

METHOD OF MAKING INSOLES.

1,022,391.

Specification of Letters Patent.

Patented Apr. 2, 1912.

Application filed November 17, 1910. Serial No. 592,823.

To all whom it may concern:

Be it known that I, GEORGE L. PREBLE, of Lynn, in the county of Essex and State of Massachusetts, have invented certain new and useful Improvements in Methods of Making Insoles, of which the following is a specification.

This invention relates to insoles of the type which comprises a plurality of layers, 10 one of which is composed of textile material which is formed with a crease or rib to receive the stitches by which the pulled-over portion of an upper is attached. Hitherto, in soles of this type the layer of textile material 15 has been joined with another layer of any suitable material, such as leather, by means of cement; but insoles depending upon cement for joining the layers are not satisfactory, because the insole is oftentimes 20 subjected to strains which pull the layers apart, the cement being insufficient for standing the strain. The present invention overcomes this weakness in the joining of the layers, by uniting the layer of textile 25 material with a layer of celluloid while the exterior of the celluloid is in a liquid condition, and pressing the two layers together while the celluloid is in a liquid condition, so that the liquid celluloid is forced into the 30 interstices of the textile material. When the celluloid becomes hard it is interlocked and clings so tenaciously to the textile material that it is impossible to separate the layers without dissolving the celluloid. The 35 celluloid acts, therefore, to positively hold the textile material in its original condition, thus preserving the formation of the stitch-receiving rib with sufficient strength to withstand any strain to which the shoe is ordinarily subjected.

It is oftentimes desirable to insert a reinforcing strip in the crease which forms the stitch-receiving portion of the insole. The present invention contemplates the use of 45 such a reinforcing strip, in which case the celluloid is caused to permeate the strip. When the celluloid is hard it is not only firmly interlocked with the fibers of the textile material but is interlocked directly with 50 the fibers of the reinforcing strip. The fact that the textile material and the reinforcing strip are interlocked in this way with the layer of celluloid positively insures the preservation of the stitch-receiving rib and 55 the reinforcing strip intact.

The celluloid, in addition to the functions

stated, renders the sole waterproof and moisture proof. It does not, however, render the sole unduly stiff, because the celluloid is sufficiently flexible. Other elements 60 may be added to those described, as, for example, a separate sock lining and a shank-stiffening member. For some purposes, however, the layer of celluloid is a suitable 65 sock lining. If a separate sock lining is added, it may be joined with the celluloid in the same manner as that by which the textile material is joined, the separate sock lining being, of course, placed upon the opposite side of the celluloid with relation to the 70 textile material. When a shank-stiffening member is added, it is preferably interposed between the sock lining and the celluloid, and the confronting faces of the shank-stiffening member and sock lining are preferably 75 coated with cement. When the shank-stiffening member is used, it, also, is preferably joined with the celluloid in the manner explained.

Of the accompanying drawings which 80 illustrate the construction of an insole and the method of assembling the various members according to the present invention: Figure 1 represents a plan view of an insole as seen from the side of the textile material. 85 Fig. 2 represents a section on line 2-2 of Fig. 1. Fig. 3 represents a cross section showing the several members assembled upon a grooved bed prior to being pressed together. Fig. 4 represents a plan view of the 90 bed, with a layer of textile material laid thereon and a flexible reinforcing strip laid upon the textile material. Fig. 5 represents a perspective view of a fragment of an insole comprising a layer of textile material 95 and a layer of celluloid. Fig. 6 represents a cross section of the various members included in Fig. 3, after being pressed together. Fig. 7 represents a cross section, on a relatively large scale, of one edge of a 100 completed sole. Fig. 8 represents a longitudinal section of the shank portion of an insole having a shank stiffener introduced between the layer of celluloid and the attached sock lining.

10 The same reference characters indicate the same parts wherever they occur.

The essential elements of the invention are a layer of textile material 10 such as canvas, duck, buckram, or other flexible material, 110 and a layer of celluloid 11. These two layers may be sufficient to constitute an insole

when they are properly united, provided the textile material is formed with a crease or rib to receive stitches. If no other element is added, the celluloid may serve as a 5 sock lining. It is usually desirable, however, to provide a separate sock lining, which may be composed of any suitable material, such as leather, felt, or woven fabric. When a separate sock lining is added, it is 10 placed upon the opposite side of the celluloid with relation to the layer 10.

As shown by Fig. 7, a separate sock lining is indicated at 12. When assembling the 15 layers 10, 11 and 12, the layer 10 is first formed to afford a stitch-receiving rib 13'. A convenient manner of forming the rib 13' is to lay the layer of textile material on a bed such as that indicated at 14, said bed being provided with a groove 15 in its working 20 engaging surface. The configuration of the groove 15 is substantially the same as that shown by the reinforcing strip 13 in Fig. 4. The textile material may be impressed into the groove 15, and if a reinforcing strip 13 25 is to be used the said strip will also be impressed into the crease formed by the rib 13'. (See Figs. 2, 6 and 7.) The layer of celluloid may then be laid upon the textile material which is thus partly embedded in the 30 groove 15. If the sole is to be composed exclusively of the two layers 10 and 11, a suitable solvent, such as wood alcohol, may be applied to one side only of the layer of celluloid. The action of the solvent reduces the 35 celluloid to a liquid condition, when it is adapted to permeate the fibers of the textile fabric and the reinforcing strip. That side of the celluloid which is rendered liquid is laid upon the textile material and then 40 pressed against the textile material with pressure sufficient to force the liquid celluloid into the textile material, between the fibers and strands thereof.

Fig. 6 illustrates a pressing member 17 45 adapted to coöperate with the bed 14 to press the two layers together. If a fibrous reinforcing strip, such as a cord, is contained in the rib 13', it too becomes permeated by the liquid celluloid. When the celluloid becomes hard, the textile material and the reinforcing strip become firmly interlocked with it, so that it is substantially impossible 50 to separate the several members without dissolving the celluloid. The merging of the celluloid with the textile material and with the reinforcing strip is represented in a conventional manner by Fig. 7. This figure 55 also includes a separate sock lining 12 with which the celluloid is also merged.

60 As shown by Fig. 8, a shank-stiffening member 16 is interposed between the sock lining 12 and the celluloid. The confront-

ing faces of the sock lining 12 and the shank-stiffening member are preferably 65 coated with cement, while the celluloid is merged with the opposite face of the shank-stiffening member as explained.

I believe that it is broadly new to combine with the layer 10 of an insole a layer of celluloid and to dissolve the celluloid sufficiently to reduce its exterior to a liquid condition and press the two layers together so that the celluloid becomes interlocked directly with the textile material. I think it 70 also broadly new to cause the celluloid to be 75 interlocked directly with the reinforcing strip 13. The reinforcing strip is not only thus directly connected with the celluloid, but it is held in position by the layer 10 which also is interlocked directly with the 80 celluloid.

I claim:

1. The herein described method of making an insole, which consists in liquefying one 85 side of a layer of celluloid, forming a layer of textile material with a stitch-receiving rib, and pressing the liquefied side of the celluloid against the textile material to cause the liquid celluloid to permeate said textile material.

2. The herein described method of making an insole, which consists in liquefying one side of a layer of celluloid, forming a layer of textile material with a crease, placing a strip of fibrous material in said crease, 95 and pressing the liquefied side of said celluloid against the textile material and the strip to cause the liquid celluloid to permeate said textile material and said strip.

3. The herein-described method of making an insole, which consists in liquefying one 100 side of a layer of celluloid, forming a stitch-receiving rib in a layer of suitable thin flexible material, and pressing the liquefied side of the celluloid against the 105 side of said flexible material away from said rib to cause the celluloid to stick thereto.

4. The herein-described method of making an insole, which consists in liquefying one 110 side of a layer of celluloid, forming a crease in a layer of suitable flexible material, placing a strip of reinforcing material in said crease, and pressing the liquefied side of said celluloid against the side of said flexible material from which said crease opens to 115 cause said celluloid to stick to said flexible material and inclose said reinforcing strip in said crease.

In testimony whereof I have affixed my signature, in presence of two witnesses.

GEORGE L. PREBLE.
